UNITED STATES PATENT OFFICE.

DUJO PLAVSA, OF BUTTE, MONTANA.

STACK-CLEANER.

1,249,483.

Specification of Letters Patent.

Patented Dec. 11, 1917.

Application filed July 9, 1917. Serial No. 179,449.

To all whom it may concern:

Be it known that I, DUJO PLAVSA, a subject of the King of Hungary, residing at Butte, in the county of Silverbow and State 5 of Montana, have invented certain new and useful Improvements in Stack-Cleaners, of which the following is a specification.

This invention relates to new and useful improvements in stack cleaner.

10 The primary object of the invention is the provision of a cleaner for stacks, such as stove pipes and flues, the same being automatically operated by the action of the wind when the device is installed upon the stack.

15 A further object of the device is the provision of an attachment for stove pipes vertically arranged for the outlet of the products of combustion, the action of the wind being utilized for shifting both vertically 20 and rotarily a cleaning member within the pipe.

A still further object of the invention is to provide a device that is easy and inexpensive to manufacture for automatically cleaning 25 a flue or stack and which may be readily attached in its operative position upon any circular stack which is already in use.

In the drawing forming a part of this application, and in which like reference 30 characters designate corresponding parts throughout the several views:-

Figure 1 is a central vertical sectional view taken through a stack provided with the present device,

35 Fig. 2 is a horizontal transverse sectional view taken upon line II—II of Fig. 1,

Fig. 3 is a similar view taken upon line III—III of Fig. 1 and

40 Fig. 4 is an enlarged detail sectional view of the follower employed with the device.

Referring more in detail to the drawing, a brick stack 10 is illustrated having a cylindrical metal pipe or stack 11 mounted upright thereon and forming the outlet for the 45 products of combustion from the main stack 10. A spider 12 is secured in the upper end of the stack 11 while a bracket 13 is secured adjacent the bottom thereof, a shaft 14 being centrally journaled through the said spider 50 and bracket axially of the stack.

A circular rib 15 is arranged upon the bracket 13 having a turntable or disk 16 revolvably mounted thereon upon ball bearings 17, while a ring 18 is carried by the 55 rib 15 overlying the edge portion of said disk for retaining the same in its shiftable

arrangement. A circular cam 19 is mounted upon the disk 16 with which a ball or roller 20 is constantly engaged, the said roller being journaled upon a radially projecting 60 arm 21 carried by the shaft 14.

A plate 22 in the form of a weather vane is mounted upon the upper end of the shaft 14 above the stack 11 whereby the shaft 14 is rotated during the action of the wind during the changes in the direction of the wind, and this action permits the roller 20 to move upwardly upon the cam 19 when the shaft 14 is violently turned as by a sudden gust of wind. The shaft 14 freely revolves in the 70 spider 12 and bracket 13 through which the same is journaled while the disk 16 will at times revolve therewith and at other times the disk will remain stationary all of which depends upon the variableness of the wind. 75

A plurality of scrapers 23 are vertically arranged adjacent the sides of the stack 10, the same being in the form of elongated strips preferably semi-circular in cross-section, each of the scrapers being mounted 80 upon a pair of arms 24 radially projecting from the shaft 14. It will be obvious that any desired number of scrapers 23 may be so employed, carried by the shaft 14 at any desirable angularity and which being in substantial contact with the flue 11 will operate thereon during the turning of the shaft 14. 85

The complete operation of the device will be readily apparent from this detailed description thereof it being noted that the elevating and lowering of the shaft 14 which takes place when the roller 20 of the arm 21 rides up and down on the cam 19 will shift the different scrapers 23 longitudinally of the stack 11 whereby the same will operate 95 in different planes and upon different surfaces of the stack during the rotation of the shaft. A serviceable stack cleaner is arranged which is entirely operable by the action of the wind and is calculated to maintain the stack free from soot and other accumulations. While the present form of the invention is preferable, minor changes may be made therein without departing 100 from the spirit and scope of the appended 105 claims:-

What I claim as new is:-

1. A cleaner comprising in combination with a cylindrical stack, a scraper shaft journaled axially thereof, a weather vane projecting from said shaft exteriorly of the stack and means adapted for imparting longitudinal 110

movement to the shaft during the rotation thereof.

2. A cleaner comprising in combination with a cylindrical stack, a scraper shaft 5 axially journaled therethrough, a weather vane secured to said shaft exteriorly of the stack, a cam revolvably mounted concentric with said shaft and means carried by the shaft engaging the said cam whereby the 10 shaft is adapted for longitudinal movement during the rotation thereof.

3. A device of the class described comprising a cylindrical stack, a spider secured adjacent the top thereof, a bracket secured adjacent the bottom of the stack, a shaft cen-

trally journaled through the said spider and bracket, a wind-engaging plate upon the upper end of said shaft scrapers upon said shaft in substantial contact with the sides of the stack, a disk antifrictionally journaled upon said bracket and through which said shaft freely extends, a circular cam upon said disk concentric with the shaft, an arm upon the shaft, and a roller journaled upon the said arm positioned and adapted for traveling upon the said cam. 20 25

DUJO PLAVSA.
